UNITED STATES PATENT OFFICE

JOHN SHANNON, OF BIRMINGHAM, ENGLAND, ASSIGNOR TO POSTERMATIC LIMITED,
OF BIRMINGHAM, ENGLAND

ADVERTISING OR DISPLAY APPARATUS

Application filed April 17, 1930, Serial No. 445,118, and in Great Britain April 20, 1929.

This invention comprises certain improvements in or relating to advertising or display apparatus of the kind comprising a cabinet having preferably a transparent panel in its front, behind which, according to the size 5 of the cabinet, a number of flexible advertising or display sheets or supports are secured, with one end of each sheet secured to an anchor roller which is rotatably mounted near the top of the cabinet, while the other ends 10 of said sheets are each secured to sheet rollers upon which they are adapted to be automatically and alternately wound and unwound. These rollers with their sheets wound or partly wound thereon, are stored in the rear part 15 of the cabinet loosely resting preferably by means of spacing discs, one on top of another, by having their spigot ends inserted into and guided in the substantially vertical rear portions of endless channels of elongated O-shape which are arranged in or near the two side walls of the cabinet. The rollers are wound by toothed wheels thereon engaging 20 stationary racks, the rollers being lifted such as by a hook or an endless chain or band. 25

This invention has for its object to provide improved means of feeding the sheet roller at the bottom of the guide groove into position for being lifted and into engagement with the toothed rack, and also for ensuring that the roller as it passes over the 30 top of the guide groove will not be permitted to tilt to cause a jamming action in the guide grooves.

According to the present improvements, 35 means are provided for positively moving the toothed wheel on the sheet roller into engagement with the stationary rack, preparatory to the roller being raised by the endless band or chain. The means for positively moving 40 the sheet roller as hereinafter described comprises a cam or pusher device which pushes the roller along a flat lower portion of the guide groove. The roller before moving into 45 engagement with the rack passes under a pressure gripping device. The cam aforementioned is arranged to also receive the sheet roller immediately above the roller to be pushed forward to thereby allow such upper roller, and the additional rollers rest- 50 ing thereon, to gradually drop without jamming. When the sheet roller is passed over the top of the guide groove it is received by a lowering device to ensure that the roller will not jam. This lowering device conve- 55 niently comprises reciprocating arms.

To ensure that the toothed wheel will always engage the teeth in the rack the bottom portion of the rack is pivotally mounted and pressed forward under spring control. 60

Referring to the drawings:—

Figure 1 is a cross-sectional elevation of the display mechanism constructed according to this invention.

Figure 2 is a front view of an anchor roller 65 constructed according to this invention.

Figure 3 is an end portion of Figure 2, showing the sheet fixing strips in position.

Figure 4 is an end view of Figure 3.

Figure 5 is a front elevation of a sheet 70 roller, and

Figure 6 is a section on line x—x of Figure 5.

The sheet rollers 1—6 have their ends mounted in guide grooves 7 of the frame- 75 work 7a of the machine, and the front roller, for instance, after having displayed the sheet carried thereby the required length of time is raised by means of a hook 33 on the endless band 8, and whilst being raised the display sheet is wound thereon. The roller 1 then passes to the position occupied by the roller 6 and the roller 2 is moved forward for displaying the sheet carried thereby. 80 According to the present improvements, each roller is successively pressed forward into engagement with the toothed rack 9 by means of a cam 10 mounted on the suitably driven rotating shaft 11, the sheet rollers being spaced apart by the discs 13. The cam 10 85 is adapted to press the sheet roller 2 forward through the intermediary of the roller 3. In the position shown the roller 1 is carried up the guide groove 7 and the roller 2 moved forward by the pressure of the roller 3. The cam 10 bears on the axle portion 12 of the roller. The roller occupying the 90 position shown by the roller 2 is held in this position by means of the spring gripping clamp head 14, and the succeeding roller 3 95 100

for instance is adapted to pass under the clamp before the roller 2 leaves the clamp. The clamp 14 has a spindle 15 slidably mounted in the block 16, and the gripping pressure is obtained by means of the springs 17 which bear against the head 14 and adjustable pins 18 screwed into the block 16. In order to ensure that the toothed wheels 1a on a sheet roller will always mesh with the teeth on the rack 9, the lower end 9a of such rack is pivotally mounted and is pressed forward by means of the spring 19. When therefore the toothed wheel 1a is moved forward, if the tip of one of the teeth moves against the tip of a tooth on the rack, such rack will be pressed back until the teeth intermesh. By the use of the clamp 14 the first roller such as 1, is free to be raised whilst the next roller 2 will be prevented from moving until actuated by the cam 10. The cam 10 is also so shaped that the roller in the position of roller 4 gradually rides down the cam, and therefore ensures that the piled up rollers will be gradually lowered and maintained in a parallel position to thereby prevent any liability of a jamming action.

When a roller is raised to the top of the groove 7 it leaves the chain 8 and is free to run into the back portion of the groove. To prevent the roller tilting during this movement, a lowering device, comprising pivoted arms 20, is provided. These arms are timed to receive the roller, and as the arms are pivoted backwardly the roller is gradually lowered without tilting. The arms 20 are conveniently fitted with a helical spring 34 in a notch 35 at the part where the rollers bear thereon. The arms 20 are reciprocated on the spindle 21 by means of the connecting link 22 and the pivoted lever 23. The lever 23 is actuated by means of the cam 24, mounted on the spindle 11, the lever 23 being maintained in contact with the cam by means of the spring plunger device 25.

The display sheets are fixed to the sheet carrier or anchor roller 26 so that they can be readily removed or fitted and so that the display sheets between the fixed ends are of the required length. For this purpose a number of collars 27 are provided and these collars have V-shaped grooves around the periphery. The display sheet is folded over two faces of the fixing strips 27a which are wedged into the grooves, thereby clamping the top of the display or like sheet in position. The ends of the strips 27a are held in position by means of a split ring 28 which engages grooves 29. The split ring has a space between the ends which enables any one of the strips 27a to be passed therethrough, thereby enabling the display sheet to be replaced with great rapidity. The spring band 30 is also engaged around the strips 27a. The spindle 31 of the sheet roll-

ers is divided longitudinally and fixed together by means of screws 32 thereby enabling the other end of the display sheet to be readily and adjustably fixed to the sheet roller.

The device may be used for displaying advertisements, station direction indications or the like.

The chain is intermittently driven in accordance with the time of display of each sheet, and the shaft 11 is continuously rotated at a suitable speed to feed and lower a roller for each intermittent movement of the chain.

Claims:

1. An advertising or display apparatus comprising a plurality of display sheets, a rotatably mounted anchor roller to which one end of each display sheet is fixed, display rollers to which the other end of each display sheet is fixed a frame having guide grooves in which the adjustable rollers travel, a rack, toothed wheels on the display rollers which engage the rack to wind the sheets thereon, means for positively and successively moving the toothed wheels on the display rollers into engagement with the toothed rack before the rollers are engaged by the lifting means, and means for lifting the rollers after the toothed wheels thereon have been engaged with the said rack.

2. An advertising or display apparatus comprising a plurality of display sheets, a rotatably mounted anchor roller to which one end of each display sheet is fixed, display rollers to which the other end of each display sheet is fixed, a frame having guide grooves in which the adjustable rollers travel, a rack, toothed wheels on the display rollers which engage the rack to wind the sheets thereon, means for positively and successively moving the toothed wheels on the display rollers into engagement with the toothed rack preparatory to the rollers being raised whilst in engagement with the rack, comprising a cam which presses the display roller along the lower portions of the guide grooves, a chain and a hook on the chain for lifting the rollers whilst in engagement with the rack.

3. An advertising or display apparatus comprising a plurality of display sheets, a rotatably mounted anchor roller to which one end of each display sheet is fixed, display rollers to which the other end of each display sheet is fixed, a frame having guide grooves in which the adjustable rollers travel, a rack, toothed wheels on the display rollers which engage the rack to wind the sheets thereon, means for positively and successively moving the toothed wheels on the display rollers into engagement with the toothed rack preparatory to the roller being raised whilst in engagement with the rack, comprising a cam which presses the display rollers along the lower portions of

the guide grooves, and a pressure gripping device under which the rollers pass when being pushed forward by the cam, a chain and a hook on the chain for lifting the rollers

5 whilst in engagement with the rack.

4. An advertising or display apparatus comprising a plurality of display sheets, a rotatably mounted anchor roller to which one end of each display sheet is fixed, display

10 rollers to which the other end of each display sheet is fixed, a frame having guide grooves in which the adjustable rollers travel, a rack, toothed wheels on the display rollers which engage the rack to wind the sheets

15 thereon, the lower end of which is adapted to pivot forwardly under spring pressure, means for positively and successively moving the toothed wheels on the display rollers into engagement with the toothed rack pre-

20 paratory to the rollers being raised whilst in engagement with the rack, a chain and a hook on the chain for lifting the rollers whilst in engagement with the rack.

5. An advertising or display apparatus

25 comprising a plurality of display sheets, a rotatably mounted anchor roller to which one end of each display sheet is fixed, display rollers to which the other end of each display sheet is fixed, a frame having guide

30 grooves in which the adjustable rollers travel, a rack, toothed wheels on the display rollers which engage the rack to wind the sheets thereon, means for positively and suc-

35 cessively moving the toothed wheels on the display rollers into engagement with the toothed rack preparatory to the rollers being raised whilst in engagement with the rack, comprising a cam which presses the display roller along the lower portion of the guide

40 groove, and which is adapted to gradually lower the heaped up rollers at the rear of the display device, a chain and a hook on the chain for lifting the rollers whilst in engage-

45 ment with the rack.

6. An advertising or display apparatus

50 comprising a plurality of display sheets, a rotatably mounted anchor roller to which one end of each display sheet is fixed, display rollers to which the other end of each display

55 sheet is fixed, a frame having guide grooves in which the adjustable rollers travel, a rack, toothed wheels on the display rollers which engage the rack to wind the sheets thereon, means for positively and successively mov-

60 ing the toothed wheels on the display rollers into engagement with the toothed rack preparatory to the roller being raised whilst in engagement with the rack, a chain and a hook on the chain for lifting the rollers whilst in engagement with the rack, and a lowering

65 device for receiving and lowering each roller as it passes over the top of the guide grooves.

7. An advertising or display apparatus

65 comprising a plurality of display sheets, a rotatably mounted anchor roller to which one

end of each display sheet is fixed, display rollers to which the other end of each display sheet is fixed, a frame having guide grooves in which the adjustable rollers travel, a rack, toothed wheels on the display rollers which engage the rack to wind the sheets thereon, and means for positively and successively moving the toothed wheels preparatory to the roller being raised whilst in engagement with the rack, a chain and a hook on the chain for lifting the rollers whilst in engagement with the rack, and a lowering device comprising oscillating arms for receiving and lowering each roller as it passes over the top of the guide grooves.

8. An advertising or display apparatus

80 comprising a plurality of display sheets, a rotatably mounted anchor roller having grooved collars thereon, fixing strips adapted to fit in the groove to fix one end of each display sheet, display rollers to which the other end of each display sheet is fixed, the rollers having toothed wheels, a frame having

85 guide grooves in which the rollers travel, a rack with which the toothed wheels on the rollers engage to wind the sheets thereon, means for positively and successively moving the toothed wheels on the display rollers into engagement with the toothed rack preparatory to the roller being raised whilst in en-

90 gagement with the rack, a chain and a hook on the chain for lifting the rollers whilst they are in engagement with the rack.

In witness whereof I have signed this specification at Birmingham, England, this 19th day of March, 1930.

JOHN SHANNON.
